UNITED STATES PATENT OFFICE.

CHARLES W. STARKER, OF PITTSBURGH, AND GUSTAV L. S. KRONFELD, OF WILKINSBURG, PENNSYLVANIA, ASSIGNORS TO WESTINGHOUSE ELECTRIC AND MANUFACTURING COMPANY, A CORPORATION OF PENNSYLVANIA.

BRUSH-HOLDER.

1,277,497.

Specification of Letters Patent. Patented Sept. 3, 1918.

Application filed June 30, 1915. Serial No. 37,231.

To all whom it may concern:

Be it known that we, CHARLES W. STARKER, a subject of the Emperor of Germany, and a resident of Pittsburgh, in the county of Allegheny and State of Pennsylvania, and GUSTAV L. S. KRONFELD, a subject of the King of Great Britain, and a resident of Wilkinsburg, in the county of Allegheny and State of Pennsylvania, have invented a new and useful Improvement in Brush-Holders, of which the following is a specification.

Our invention relates to current-collecting devices for dynamo-electric machines and it has for its object to provide a device of the character specified that shall be particularly simple and inexpensive in construction and reliable in operation.

According to the present invention, we provide a current-collecting device or brush holder, the body portion of which is formed entirely of pressed metal. Furthermore, we provide a brush holder that is equipped with a plurality of readily adjustable resilient members for engaging the current-collecting members or brushes.

In the accompanying drawings, Figure 1 is a plan view of a brush holder constructed in accordance with our invention; Fig. 2 is a view, in side elevation, of the brush holder shown in Fig. 1; Fig. 3 is a plan view of the pressed metal body portion of the brush holder; Fig. 4 is a view, partially in section and partially in front elevation, of the body portion shown in Fig. 3; Fig. 5 is a view, in side elevation, of the body portion shown in Fig. 3; Fig. 6 is a sectional view along the line II-II of Fig. 1, showing the brush-retaining means; Fig. 7 is a sectional view along the line IV-IV of Fig. 6, and Fig. 8 comprises two detail views of the brush contact hammer.

A current-collecting device or brush holder 1 comprises a body member 2 and a brush-box member 3 that is secured to the body member 2 by rivets 4 or any other suitable means. As best shown in Figs. 3, 4 and 5, the body member 2 comprises a dish-shaped portion 5 and a pair of oppositely disposed and laterally extending pockets 6. The pockets 6 are formed integral with the side walls of the dish-shaped portion 5 and are approximately circular in form. Each of the pockets 6 is provided with a central

opening 7 and a substantially annular flange 8 surrounding the opening. Each of two supporting rods 9 is provided with an enlarged portion 10 and with a threaded extension 11 of somewhat smaller outside diameter than the diameter of the central opening 7 in the pocket 6. The rods 9 are mounted upon the body member 2 of the brush holder 1, with the enlarged portions 10 fitting closely within the pockets 6 and with the threaded extensions 11 projecting through the openings 7. Nuts 12 coact with the threaded extensions 11 to secure the enlarged portions 10 within the pockets 6. The supporting rods 9 are adapted to be secured to the frame of a dynamo-electric machine in any suitable manner and are insulated therefrom by an insulating bushing 13 and an insulating sleeve 14, as best shown in Fig. 2. It is evident that the brush holders may be removed readily from their supporting rods 9 without removing the rods from the frame of the dynamo-electric machine.

The brush holder 1 is further provided with a current-collecting member or brush 15 that is adapted to slide within the brush box 3 and with pressure devices 16 to maintain the brush 15 in operative engagement with a commutator cylinder 17. As best shown in Figs. 6 and 7, the devices 16 comprise springs 18 and spring guides 19 of substantially a U-shape cross-section. The innermost turns of the springs 18 terminate in straight portions 20 and are secured within a slot 21 in a shaft 22. The shaft 22 is rotatably mounted in suitable openings 23 in the side walls of the body member 2 and is supported, at a point intermediate the openings 23, by a bracket 24. The bracket 24 comprises a base portion 25 secured to the bottom of the dish-shaped portion 5 by rivets 25a, or in any other suitable manner, and an upwardly extending portion 26. The portion 26 is provided with an opening 27 to receive the shaft 22. A ratchet wheel 28 is rigidly secured to the shaft 22 by means of a cotter pin 29 which engages registering holes in the ratchet wheel hub 30 and the shaft 22. A pawl 32 is pivotally mounted on the upwardly extending portion 26 of the bracket 24 and is adapted to engage the teeth 33 of the ratchet wheel 28. The pawl 32 is provided with an extension

34 that projects above the walls of the portion 5 and which may be utilized to disengage the pawl from the teeth 33 of the ratchet wheel 28. The hub 30 of the ratchet wheel is provided with a plurality of openings 35 which are adapted to receive a suitable rod or pin in order to rotate the ratchet wheel 28 against the tension of the springs 18. The spring guides 19 are provided with hubs 36 for rotative engagement with the shaft 22. The guide members 19 further comprise finger portions 38 that terminate in approximately semi-circular extensions 39. The outermost turns of the spring members 18 are extended to form finger portions 40 which terminate in approximately semi-circular portions 41 that are oppositely disposed with respect to the portions 39. As best shown in Fig. 2, flexible conductors 42 are secured to an upwardly extending portion 43 of the brush holder body member 2 and are disposed along the under sides of the U-shape guide members 19. The flexible conductors 42 terminate adjacent the semi-circular portions 39 and 41 and the latter are engaged by a clip 44. As best shown in Fig. 8, the clip 44 comprises cylindrically curved portions 45 and laterally extending portions 46. The portions 45 embrace the portions 39 and 41 and the flexible conductor 42 and thereby form a substantially unitary structure. The clip 44 is preferably formed of material having high electrical conductivity so that current may be taken from the brush 15 and through the flexible conductor 42 with relatively little heating of the spring members 18.

From the foregoing, it is apparent that a pressed metal brush holder constructed in accordance with my invention may be readily removed from its supporting rods. Furthermore, by having a single ratchet-and-pawl mechanism for controlling the tension of the brush-retaining members, the amount of pressure exerted upon the brushes will always be kept constant and may be easily adjusted.

While we have shown our invention in a suitable and preferred form, it is not so limited but is susceptible of various minor changes and modifications within the scope of the appended claims.

We claim as our invention:

1. A brush holder embodying a one-piece body member comprising a dish-shaped portion having the mid-portion of its oppositely disposed side walls bent outwardly to form a plurality of pockets.

2. A brush holder comprising a body portion provided with laterally extending and approximately cylindrical pockets having central apertures, supporting rods extending through the said apertures and provided with enlarged portions seated within the said pockets and portions projecting beyond said

pockets, and retaining members coacting with said projecting portions.

3. A current-collecting device comprising a dish-shaped body member, current-collecting members carried thereby, a shaft mounted at its ends in the walls of said body member, resilient members for engaging said current-collecting members mounted in side-by-side relation on said shaft, a ratchet wheel carried by said shaft between said resilient members and an adjusting pawl mounted on an upwardly extending projection of said body member and having an operating portion projecting above the walls of said body member. 80

4. A current-collecting device comprising a dish-shaped body member, current-collecting members carried thereby, a shaft mounted at its ends in the walls of said body member, resilient members for engaging said current-collecting members mounted in side-by-side relation on said shaft, a ratchet wheel carried by said shaft between said resilient members, an upwardly extending bracket for said shaft located adjacent to said ratchet wheel and an adjusting pawl pivotally mounted on said bracket and having an operating portion projecting above the walls of said body member and between said resilient members. 85

5. A current-collecting device comprising a current-collecting member, a holding member therefor, a shaft, a resilient member for engaging said current-collecting member mounted on said shaft, a guide member rotatably mounted on said shaft and embracing said resilient member, the said resilient member and the said guide member respectively terminating in oppositely disposed semi-cylindrical portions and means for securing said portions together. 100

6. A current-collecting device comprising a current-collecting member, a holding member therefor, a shaft, a resilient member for engaging said current-collecting member mounted on said shaft, a guide member rotatably mounted on said shaft and embracing said resilient member, the said resilient member and the said guide member respectively terminating in oppositely disposed semi-cylindrical portions and a cylindrically curved contact tip surrounding said portions and securing them together. 110

7. A current-collecting device comprising a current-collecting member, a holding member therefor, a shaft, a resilient member for engaging said current-collecting member mounted on said shaft, a guide member for said resilient member, and a flexible conductor secured at one end to said holding member and having a portion thereof carried by said guide member. 120

8. A current-collecting device comprising a current-collecting member, a holding member therefor, a shaft, a resilient member for 125

engaging said current-collecting member mounted on said shaft, a U-shaped guide member, the arms of which embrace said resilient member and a flexible conductor secured at one end to said holding member and having a portion thereof located between the arms of said guide member.

9. A current-collecting device comprising a current-collecting member, a holding member therefor, a shaft, a resilient member for engaging said current-collecting member mounted on said shaft, a guide member rotatably mounted on said shaft and embracing said resilient member, the said resilient member and the said guide member respectively terminating in oppositely disposed semi-cylindrical portions, and a flexible con-

ductor secured at its ends to said holding member and between said semi-cylindrical portions, respectively, and having a portion 20 thereof carried by said guide member.

10. A brush-holder embodying a one-piece body member comprising a dish-shaped portion having its oppositely disposed side walls projecting outwardly to form a plurality of 25 pockets, each having cylindrical side walls and a bottom and being laterally disposed with respect to the said body member.

In testimony whereof we have hereunto subscribed our names this 21st day of June, 30 1915.

CHARLES W. STARKER.
GUSTAV L. S. KRONFELD.
